UNITED STATES PATENT OFFICE.

JOHN HENRY SWIHART, OF CLEVELAND, OHIO, ASSIGNOR TO THE NATIONAL COMPUTING SCALE COMPANY, OF SAME PLACE.

DESIGN FOR A FACE-PLATE FOR SCALES.

SPECIFICATION forming part of Design No. 27,607, dated August 31, 1897.

Application filed June 7, 1897. Serial No. 639,762. Term of patent 14 years.

To all whom it may concern:

Be it known that I, JOHN HENRY SWIHART, a citizen of the United States, residing at Cleveland, in the county of Cuyahoga and State of Ohio, have invented and produced a new and original Design for a Face-Plate for Scales, of which the following is a specification, reference being had to the accompanying drawing, forming a part thereof.

10 The drawing is a front elevation of a face-plate for scales, showing my design.

The leading features of my design consist of a circular face-plate having one long horizontal opening extending outward from a point near the center to a point near the circumference and a segmental opening near the circumference. As shown, one end of the segmental opening joins with the outer

end of the horizontal opening; but these ends do not necessarily join and may be separated by a thin partition, as indicated by the dotted lines.

Referring to the parts by letters, A represents the plate, and B and C the horizontal and segmental openings, respectively. The center of the plate is also the center of the opening C.

What I claim is—

The design for a face-plate for a scale, substantially as herein shown and described. In testimony whereof I affix my signature in presence of two witnesses.

JOHN HENRY SWIHART.

Witnesses:

E. L. THURSTON,
CHARLES A. HOYT.
